MULTIPLE HOIST APPARATUS

Donald W. Schaper, Alliance, Ohio, assignor to The Morgan Engineering Company, a corporation of Ohio

Filed Aug. 18, 1958, Ser. No. 755,485

13 Claims. (Cl. 254—188)

This invention relates to hoists and particularly to hoists adapted to provide a multiple number of hoist capacities.

An object of my invention is to provide in a single apparatus an arrangement for converting a hoist to a selected mechanical-advantage ratio of a plurality of available arrangements for different mechanical-advantage ratios.

Another object is to provide an apparatus which may be converted by simple adjustments from a hoist capable of lifting relatively heavy loads at slow speed to a hoist capable of lifting relatively lighter loads at relatively faster speeds.

Another object is the provision for combining in one hoisting apparatus an arrangement for a hoist of one lifting capacity and a hoist of another lifting capacity without duplication of hoists.

Another object is the provision of a hoisting mechanism which in effect provides automatic re-reeving by selectively including some sheaves in the pulley arrangement and omitting other sheaves in the pulley arrangement.

Another object is to provide a cable hoist having dual or multiple functions, that is, providing different mechanical-advantage ratios as required.

Another object is the provision for simple and readily operable controls for changing a hoisting mechanism from one reeving arrangement to another reeving arrangement without removal of the cable from the sheaves.

Another object is the provision for a readily adjustable mechanism for the changing of a cable hoist from one lifting capacity to another lifting capacity.

Another object is the provision for quick change-over from a cable hoist having one speed and weight-lifting capacity to another cable hoist having another speed and weight-lifting capacity.

Another object is the provision for obtaining improved results in a new and improved manner.

Other objects and a fuller understanding of the invention may be had by referring to the following description and claims, taken in conjunction with the accompanying drawing, in which:

Figure 1 shows a side elevational view partially in section of a hoisting mechanism embodying my invention and showing the parts in one arrangement;

Figure 2 is a side elevational view of a hoist embodying my invention and showing the parts in another position;

Figure 3 is a side elevational view of a hoist embodying my invention and showing the parts in still another position;

Figure 4 is a longitudinal sectional view taken through the line 4—4 of Figure 1 and showing details of the construction of the hoist;

Figure 5 is an enlarged detailed view showing the coupling or catch member for coupling and uncoupling the upper and lower pulley blocks of the movable sheave assembly; and

2

Figure 6 is an enlarged perspective view of a spring used for holding the coupling or catch member in different alternative positions.

In the drawing, parts are shown partially diagrammatically and somewhat out of the usual arrangement in order to better illustrate the principle of the invention and to show the relationship of the parts.

A hoisting drum 11 carried by a trolley or crane is driven by an electric motor in a manner to wind and 10 unwind a cable 12 about the hoisting drum 11. The cable 12 is in two sections with ends of the cable 12 being simultaneously wound around axially aligned sections of the wind-up drum 11.

The opposite ends of the two sections of the hoisting 15 cable 12 are anchored to two equalizer arms 13 having their one ends pivotally carried on the trolley or crane by a pivot support 14 and having their opposite corresponding ends loosely fitted in a crossbar 15 in such manner that when one equalizer bar 13 is raised, the 20 other equalizer bar is lowered by the tilting of the crossbar 15 upon a pivot support 16 equidistant of its ends, the pivot support 16 also being supported by the trolley or crane. As is known, the equalizer bar arrangement tends to maintain the two sections of the cable 12 in 25 equal tension should there be stretching or contraction of one cable section relative to the other.

The cable 12 made up of twin sections is reeved about 30 a pulley block 21 which is supported by the trolley or crane and around a movable pulley block assembly made up of upper pulley blocks 23 and the lower pulley block 26. As seen in the drawing, the two twin sections of the 35 cable 12 are reeved around the sheaves of the trolley-supported pulley block 21 and the assembly of pulley blocks 23 and pulley block 26 in such manner that mechanical advantage is obtained by the winding up 40 of the cable 12 on the hoisting drum 11 with the opposite ends of the cable sections being supported by the ends of the two equalizer bars 13.

The trolley-supported pulley block 21 is carried on 45 a shaft 22 in such manner that the pulley block 21 has a fixed axis relative to the trolley or crane upon which it is carried. In the embodiment of the invention illustrated, there are four sheaves 21-a, 21-b, 21-c and 21-d included in the pulley block 21, the sheaves 21-a and 21-b being disposed adjacent one end of the shaft 22 and the sheaves 21-c and 21-d being disposed adjacent the other end of the shaft 22. Also carried by the 50 trolley or crane and in fixed position relative to the pulley block 21 is an upper stop pad 17 having a horizontally disposed surface adapted to meet and abut the movable pulley blocks upon being raised upwardly in close proximity to the pulley block 21. There is a downwardly extending projection 18 from the stop pad 17 which is so positioned as to be able to fit or extend between the upper portions of the two pulley blocks 23 55 upon these pulley blocks 23 being moved up against the stop pad 17. Extending in a horizontal plane and parallel to each other are two lock pins 19 which lock pins may be moved along their respective axes by solenoids 60 arranged to be electrically energized and controlled from the operator's position or cab. These two lock pins 19 have their ends cam-shaped and they are spring-biased so as to automatically engage the pulley block 23 upon movement of the pulley blocks upwardly against the stop pad 17.

There are two movable pulley blocks 23 which are spaced apart along their common axis. The pulley blocks 23 include sheaves 23-a, 23-b, 23-c and 23-d journaled on a shaft 24. Sheaves 23-a and 23-b are disposed adjacent one end of the shaft 24 and sheaves 23-c and 23-d are disposed adjacent the other end of the shaft 24. A housing 25 encloses the aligned spaced pulley blocks 23.

except where the cable 12 extends from the pulley blocks 23 to the trolley supported block 21, there being openings in the housing 25 to accommodate the cable 12 passing therethrough. In alignment with each other and extending toward each other from the inner faces of the housing 25 are sets of ears 25-b. Extending through each set of ears 25-b are aligned openings 25-c. The arrangement is such that when the pulley blocks 23 are raised upwardly to engage the stop pad 17, the ears 25-b embrace the projection 18 of the upper stop pad 17 and the openings 25-c are in alignment with the lock pins 19. The lock pins 19 being spring-biased and having cammed ends slip into the openings 25-c so as to lock or couple the housing 25 of the blocks 23 to the stop pad 17.

By electrically energizing the solenoid to move the lock pins 19, the lock pins 19 are disengaged from the openings 25-c and the pulley blocks 23 are then uncoupled or disengaged from their fixed position relative to the stop pad 17 and are thus able to again move up and down relative to the trolley supported pulley block 21. The lower pulley block 26 carrying the two sheaves 26-a and 26-b journaled on a shaft 27 is enclosed by a housing 28 except for openings therethrough for accommodating the cable 12 which is reeved around the sheaves 26-a and 26-b. The lower pulley block 26 and its housing 28 are so dimensioned and disposed as to interfit between the lower portions of the spaced inner faces of the housing 25 closing the spaced blocks 23. The lower end of the housing 28 of the lower or intermediate pulley block 26 carries a transverse pin 30, which in turn carries a hook or load-engaging member 29. The hook 29, as in the usual case, is adapted to engage a pin or cable which supports a load to be hoisted by the hoisting apparatus.

As seen in the drawing, the top of housing 28 is positioned below the housing 25 at a location intermediate the ends of housing 25 so that raising of the housing 28 also raises housing 25.

The lower ends of the portions of the housing 25 enclosing the pulley blocks 23 have lower projections 25-a, upon which are pivotally supported by pivots 32 coupling or catch members 31. The coupling members 31 are arranged opposite each other so that their lower ends may be swung toward and away from each other. The upper ends of the coupling members 31 above their respective pivot supports 32 have angularly disposed end surfaces 31-a. A pair of forked leaf springs 33 are carried by the housing 25 in such manner that the free ends of the springs 33 straddle the projection 25-a and press downwardly upon the angular end surface of the respective coupling members 31. By the spring tension provided by spring members 33, the coupling members 31 may be swung into and maintained in alternative positions such as in the positions shown in full lines and dotted lines, respectively, in Figure 5.

The lower ends of the coupling members 31 have openings 31-b extending therethrough and these openings 31-b are adapted to fit over and engage with bosses or fingers 34 projecting outwardly away from each other from the housing 28 of the lower or intermediate block 26. The bosses or fingers 34 are downwardly hooked so as to firmly interlock with the coupling members 31 when the coupling members 31 are swung toward each other against the housing 28 and the housing 28 moved down relative to the housing 25. The coupling members 31 may be readily and manually disengaged from the fingers 34 by unhooking the coupling members 31 from under and around the respective fingers 34. The tension provided by the springs 33 can hold the coupling members 31 away from each other so as not to engage accidentally with the fingers 34. However, the tension of the springs 33 may be overcome so as to move the coupling members 31 toward each other and to interlock with the hooked bosses or fingers 34.

By the arrangement shown, the lower or intermediate

block 26 may be readily and effectively assembled with the upper or side pulley blocks 23 so that one pulley block assembly or single operative unit may be provided. When so assembled, the blocks 23 and the block 26 may move up and down together as a unit relative to the trolley-supported block 21 as the hoisting drum 11 winds and unwinds the cable 12. Also by manually unlocking the coupling members 31 from the fingers 34, the lower or intermediate block 26 may be made independent of the blocks 23 so that movement of the block 26 and the load carried on the hook 29 may be independent of the movement or lack of movement of the blocks 23. Inasmuch as the coupling members 31 may be readily and manually moved by a rigger to the coupled position or uncoupled position when the blocks 23 and 26 are in lowered position near the floor or ground surface, it may not be necessary to provide other means for moving the coupling members 31 to locked or unlocked position. Of course, as the projection 18 and locking pins 19 are at an elevated position, it is preferred to provide a remotely controlled actuating mechanism, such as an electric solenoid, for moving the locking pins 19 to an unlocked position when required or, if desired, to move by the solenoid the locking pins to both locked and unlocked positions.

To prevent over-running of the hoisting apparatus in a direction which would violently raise the movable blocks as an assembly upwardly against the stop member 17, a pair of stop arms 36 and 36-a is provided. Arms 36 and 36-a are so positioned as to be engaged by the top surface of the housing 28 of the lower or intermediate block 26 when the block 26 is moved upwardly toward the trolley-supported block 21. The stop arm 36 is spring-biased to a normally horizontal position by a spring 38. A guide pin or rod 39 within the coil spring 38 keeps the spring 38 in proper alignment and also limits compression of the spring 38 beyond a permitted amount. Correspondingly, the stop arm 36-a, which is in balance with the arm 36, is spring-biased by a spring 38-a around a guide pin or rod 39-a to also bias the arm 36-a to a normally horizontal position. The upper ends of the springs 38 and 38-a abut against abutment members 41 and 41-a, respectively, which are carried by the trolley or crane. The function of the stop arm 36-a is to balance the stop arm 36, which in turn actuates a limit switch assembly. The arm 36 has a connecting rod 40 which is reciprocal as the arm 36 swings up and down. The upper end of the connecting rod 40 is pivotally connected to the outer end of a switch arm 42 pivotally mounted on a pivot support 43 carried on the abutment member 41. There are a pair of electrical contact elements 45 and 46 electrically insulated by insulation member 44 carried on the abutting member 41. Electrical lead 47 connects with the contact element 45 and electrical lead 48 connects with the contact element 46. The leads 47 and 48 lead to controls for the electric motor which operates the hoisting drum 11.

As is seen in Figure 2, the contact element 46 is movable and the contact element 45 is fixed. When the stop arm 36 is in its normally horizontal position, such as shown in Figures 1 and 3, contact elements 45 and 46 are in engagement, and current flows between the electrical leads 47 and 48 so as to permit electrical energization of the electric motor driving the drum 11 in the hoisting direction. However, when the stop arm 36 is raised or tilted sufficiently upwardly by the upwardly moving housing 28 of the lower or intermediate block 26, then the movable contact element 46 is moved away from the fixed contact element 45 so as to break the circuit and to de-energize the drum operating motor. The arms 36 and 36-a may move from the normal horizontal position shown in Figures 1 and 3 to the extreme tilted positions shown in dotted lines in Figure 2. However, as soon as the lower block 26 has been moved upwardly to the position shown in Figure 2, the electrical

contact in the hoisting circuit is broken and the hoisting drum is no longer operated.

Springs 38 and 38-a are so tensioned and provide such bias that when the blocks 23 and 26 are uncoupled and the drum 11 is revolved in hoisting direction, the arms 36 and 36-a will at first physically hold down the block 26 while the blocks 23 move up into engagement with the pad 17. However continued hoisting upward by drum 11 on the cable will then raise the block 26 upward sufficiently to overcome the bias of springs 38 and 38-a and to tilt the arms 36 and 36-a sufficiently to disengage the contact points 45 and 46 and thus terminate flow of current in the hoisting circuit for the drum actuating motor.

(It is to be understood that counterweights or other biasing arrangements may be utilized in place of springs 38 and 38-a.)

When the blocks 23 and 26 are coupled together and move upwardly together to where the housing 28 of block 26 engages the arms 36 and 36-a, then continued upward hoisting movement of the blocks 23 and 26 by the drum 11 pulling on the cable causes the arms 36 and 36-a to tilt sufficiently that the upwardly tilted arm 36 causes separation of contact points 45 and 46 and the termination of flow of current in the hoisting circuit to the drum-actuating motor.

In the preferred operation of the apparatus, to use the hoist with all sheaves of blocks 26 and 23 in effective operation to provide one mechanical advantage ratio, the blocks 26 and 23 are coupled together to move up and down as a unit. The limit switch is thus actuated by upward movement of both units together beyond the point permitted by housing 28 of block 26 engaging and raising arm 36 sufficiently to separate contact points 45 and 46. In the usual use of the apparatus with blocks 26 and 23 coupled, the apparatus is operated so that blocks 26 and 23 are operated in a range below the arms 36 and 36-a and thus with the limit switch functioning only as a standby safety feature.

In the preferred operation of the apparatus, to use the hoist with only sheaves of block 26 in the functioning of the hoist and the sheaves of blocks 23 held out of operation, though still reeved with the other sheaves of the hoist, the operator has blocks 26 and 23 uncoupled. The operator then actuates the drum 11 in hoisting direction and this raises the blocks 26 and 23. When close to the pad 17, the operator actuates the drum at a slow speed. The bias of the springs 38 and 38-a on arms 36 and 36-a tends to hold the housing 28 and block 26 down, but the blocks 23 move up to engage the pad 17 at which position the lock pins 19 slide into and engage in openings 25-c. By the operator then actuating the drum in a lowering direction, the block 26 is lowered and the hoist is now operable at another capacity in which the mechanical-advantage ratio is different than when blocks 23 were coupled with block 26 and movable up and down therewith.

In Figure 1, the blocks 23 and 26 are locked together so as to operate as one unit. The limit switch described will limit upper travel of the assembled blocks 23 and 26 in the usual manner so as to prevent the assembled blocks 23 and 26 moving upwardly too close to the stop pad 17. If the assembly of blocks 23 and 26 coupled together as a unit should be raised too high relative to the stop pad 17, then the limit switch will cut off current to the drum-operating motor in the usual manner.

The interfitting of the parts assembled in Figure 1 is also illustrated in Figure 4. In Figure 4 it is seen that the stop arm 36 is positioned over the lower or intermediate block 26, but not over the upper or side blocks 23. However, as the lower or intermediate block 26 and the side or upper blocks 23 are coupled together as a unit in Figures 1 and 4, the stop arm 36 is effective to limit upward movement of the unit assembly made up of blocks 23 and 26.

To change over from the hoist providing the mechanical-advantage ratio shown in Figures 1 and 4, the assembly of blocks 23 and 26 is lowered together to within reach of the rigger or man on the floor or ground surface. The rigger manually unlocks the coupling members 31 from the fingers 34 so that the lower block 26 and its housing 28 are independent of the blocks 23 and housing 25. Without any load on the hook 29, the operator then energizes the drum-operating motor to wind up the cable on the drum 11. This raises the blocks 23 and 26 upwardly so that the upper blocks 23 and lower block 26 move together to the position shown in Figure 2. This, as shown in Figure 2, causes the lower block 26 to be stopped (preferably during slow operation of the drum 11) by the stop arms 36 and 36-a resiliently biased to horizontal position, and this further causes the blocks 23 to be slowly raised still further upwardly to where the top surface of the housing 25 engages the stop pad 17 and to where the locking pins 19 are aligned with the respective openings 25-c. The spring-biased locking pins 19 now interlock with the openings 25-c so as to firmly and securely couple the housing 25 and blocks 23 to the stop pad 17 and thus to hold the blocks 23 on an axis fixed in relationship to the axis of the trolley-supported block 21. This, in effect, places the blocks 23 out of operation as the blocks 23 may neither move upwardly or downwardly when in this locked position notwithstanding the winding or unwinding of the drum 11. Upon the lowering movement of the drum 11 so as to allow the cable to unwind, the weight of the lower block 26, its housing 28, and the hook 29 is such as to move downwardly away from the stop arms 36 and 36-a. The motor through its control may now be actuated so as to operate the drum to lower the hook 29 carried by the lower block 26. When the lower block 26 moves downwardly, the upper blocks 23 are held in raised position by the interlocking of the pins 19 in the openings 25-c of the housing 25. The apparatus is now in condition for operation as an auxiliary hoist which is operable at a higher speed but lesser lifting capacity. This in effect provides another hoist of another capacity but without re-reeving the cable about the sheaves of the several blocks. The hoisting apparatus may now be operated in the usual manner to raise loads carried on the hook 29. With the blocks 23 in raised and locked position, they are effectively out of operation and a hoist arrangement of another mechanical-advantage ratio is provided.

It is thus seen that multiple function of hoists is provided with one apparatus without re-reeving but merely by placing some of the sheaves out of effective operation. Although by the hoisting apparatus illustrated there are provided two different hoisting arrangements, each of a different mechanical-advantage ratio, it is seen that a greater number of hoist arrangements, each having a different mechanical-advantage ratio, may be provided while using the principle of my invention.

The invention provides for economy and for compactness in hoisting apparatus while permitting flexibility and variety of functions so as to permit the one hoisting apparatus to give different hoisting capacities and operating speeds as may be required.

The present disclosure includes that contained in the appended claims, as well as that of the foregoing description.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and scope of the invention as hereinafter claimed.

What is claimed is:

1. In a pulley system, the combination of a first pulley

block having a plurality of pulleys disposed on axes fixed relative to each other, a second pulley block having a plurality of pulleys, some of the latter pulleys being disposed on axes adapted to be displaced relative to the axes of other of the latter pulleys, said some of the latter pulleys being divided into two groups of pulleys axially spaced apart to accommodate therebetween said other of the latter pulleys, the total number of said some of the latter pulleys being equal to the total number of the pulleys in said first pulley block, cable means reeved about the pulleys of said first and second pulley blocks for providing mechanical advantage in moving one pulley block relative to the other, one of said pulley blocks being supported and the other of said pulley blocks being movable relative to the other, first selectively operable interlocking means for maintaining the axes of the said latter pulleys of said second pulley block in fixed relationship to each other, said latter pulleys of the said second pulley block being separable to permit the axes of some of the latter pulleys to be movable relative to the axes of other of the latter pulleys upon the unlocking of said first selectively operable interlocking means, second selectively operable interlocking means for maintaining the axes of said some of the latter pulleys in fixed relationship to the axes of the pulleys of said first pulley block, said second interlocking means including automatic locking means operable upon moving said some of the latter pulleys proximate to said first pulley block and including solenoid means for releasing said automatic locking means, the arrangement of pulley blocks and first and second interlocking means providing for one mechanical advantage by said cable means and pulley blocks upon the axes of said some of the latter pulleys being maintained in fixed relationship to the other of the latter pulleys of the second pulley block and for another mechanical advantage upon the axes of said some of the latter pulleys being movable relative to the axes of the other of said latter pulleys and maintained in fixed relationship to the axes of the pulleys of said first pulley block.

2. In a hoist, an upper pulley block, a plurality of lower pulley blocks, a cable reeved about said pulley blocks to provide mechanical advantage, load-engageable means carried by one of said lower pulley blocks, connecting means for readily connecting and disconnecting said lower pulley blocks, said lower pulley blocks upon being connected being movable together relative to said upper pulley block to provide a first mechanical advantage ratio, said one lower pulley block being movable relative to the other of said lower pulley blocks upon disconnection of said lower pulley blocks, locking means for locking said other of the lower pulley blocks in fixed relationship to the upper pulley block means for automatically terminating hoisting movement of the hoist upon upward movement of said one lower pulley block beyond a point spaced from said upper pulley block, and biasing means for yieldably restraining upward approach of said one lower pulley block beyond said point while said other lower pulley block moves upwardly beyond said point to the position of said fixed relationship, said one lower pulley block, upon disconnection of said lower pulley blocks and the locking of said other of the lower pulley blocks in fixed relationship to the upper pulley block, providing a second mechanical advantage ratio.

3. In a pulley system, the combination of an upper pulley block carrying a plurality of pulleys, said upper pulley block having pulley axes in fixed relationship to each other, a plurality of lower pulley blocks carrying a plurality of pulleys, said lower pulley blocks having a plurality of parallel pulley axes, a load-engaging member carried by one of said lower pulley blocks, a cable reeved on said pulleys to provide mechanical advantage in moving the load-engaging member relative to the upper pulley block, first locking means for selectively interengaging said lower pulley blocks to position the pulley

axes thereof in fixed relationship to each other and for selectively disengaging said lower pulley blocks to permit displacement of the axes of the lower pulley blocks from each other, second locking means for selectively interengaging the upper pulley block with a lower pulley block other than said one lower pulley block carrying the load-engaging member, means for automatically discontinuing the raising movement of the system upon approach of said one lower pulley block to within a limited distance of the upper pulley block, and biasing means biasing the said one lower pulley block against upward approach to said upper pulley block to within said limited distance during the approach of said other pulley block to a position within said limited distance for interengagement with said upper pulley block, the operation of the said pulley system with the lower pulley blocks interengaged providing one ratio of mechanical advantage and the operation of said pulley system with the lower pulley blocks disengaged and the upper pulley block interengaged with the said lower pulley block other than said one lower pulley block carrying the load-engaging member providing another ratio of mechanical advantage.

4. In a pulley system, first, second and third pulley blocks, cable means reeved about said pulley blocks for mechanical advantage, first interlocking means for selectively interlocking the second and third pulley blocks to move together relative to the first pulley block upon operation of the pulley system, second interlocking means for selectively interlocking the first and second pulley blocks to provide for movement of the third pulley block relative to the first and second pulley blocks upon operation of the pulley system, means for automatically stopping the hoisting movement of the cable means of said system upon approach of the third pulley block toward the first pulley block beyond a point spaced from the first pulley block, and biasing means yieldably delaying movement of the third pulley block toward the first pulley block beyond said point during the movement of the second pulley block toward the first pulley block beyond said point, operation of the pulley system with the second and third pulley blocks interlocked and movable relative to the first pulley block providing one ratio of mechanical advantage and operation of the pulley system with the first and second pulley blocks interlocked and the third pulley block movable relative to the interlocked first and second pulley blocks providing another ratio of mechanical advantage.

5. In a cable hoist operable by an electric motor having a hoisting electrical circuit and a lowering electrical circuit, an upper pulley block having pulleys on axes fixed relative to each other, a lower pulley block having pulleys on first axes and pulleys on second axes, cable means reeved about said pulleys to move the lower pulley block relative to the upper pulley block, said lower pulley block having separable parts each carrying pulleys and permitting displacement of the first axes and second axes relative to each other, readily engageable first coupling means having complementary portions carried by the respective parts for coupling said parts together to provide for movement of said parts together and maintenance of the relative positions of said first and second axes of the lower pulley block, a load-engaging member carried by one of said parts for engaging a load to be hoisted, a stop member mounted in fixed position relative to the upper pulley block, readily engageable second coupling means having complementary portions carried by said stop member and by the other of said parts for coupling said stop member and other of said parts together, limit switch means electrically connected with said hoisting electrical circuit and positioned to be actuated by said one of said parts upon approach to the upper pulley block to control said hoisting electrical circuit and to thereby limit upward movement of said one of said parts toward said stop member, and means for biasing said one of said parts against movement toward said stop member

beyond a point spaced from said stop member during the approach of the other of said parts beyond said point to a position for coupling with said stop member.

6. In a cable hoist operated by an electric motor having a hoisting electrical circuit and a lowering electrical circuit, said hoist having a stop member and having a limit switch device electrically connected to said hoisting electrical circuit and operable to terminate hoisting operation of the hoist, the combination of first pulley block means, second pulley block means and third pulley block means, cable means reeved about said first, second and third block means, said first block means having a fixed axis relative to the stop member, said second and third block means having axes movable relative to each other and to the axis of the first block means, first coupling means for selectively coupling together the second and third block means to maintain the relative positions of the axes of the second and third block means upon operation of the hoist, second coupling means for selectively coupling together the stop member and said third block means to maintain the relative positions of the axes of the first and third block means, said second block means being positioned to actuate the limit switch device upon the approach of the second block means alone and coupled with said third block means upwardly toward said stop member, and means for yieldably delaying the approach of the second block upwardly toward said stop member beyond a point distant from said stop member during the upward approach of the third block means beyond said point toward said stop member for coupling to said stop member by said second coupling means.

7. The combination in an electric motor operated cable hoist having a hoisting electrical circuit of, a first plurality of sheaves journaled on fixed axes, a second plurality of sheaves journaled on a movable axis, a third plurality of sheaves journaled on a movable axis, cable means reeved around said first, second and third pluralities of sheaves to raise the third plurality of sheaves, a load-engaging member carried by the third plurality of sheaves, the axes of the second and third pluralities of sheaves being movable by said cable means toward the axis of the first plurality of sheaves upon the raising of the third plurality of sheaves and load-engaging member, limit switch means adapted to be electrically connected to said hoisting electrical circuit and operable by the approach of the third plurality of sheaves upwardly toward the first plurality of sheaves to terminate upward operation of the hoist, stop means limiting upward movement of the second plurality of sheaves relative to the first plurality of sheaves, and coupling means for selectively coupling and uncoupling the second plurality of sheaves and third plurality of sheaves, said second and third pluralities of sheaves upon being coupled being movable as a unit relative to the first plurality of sheaves and said third plurality of sheaves upon being uncoupled from the second plurality of sheaves being movable relative to the first plurality of sheaves independently of the second plurality of sheaves, and means for delaying the operation of said limit switch means by the said approach of the third plurality of sheaves toward the first plurality of sheaves until the second plurality of sheaves engages said stop member.

8. In a cable hoist operable by an electric motor having a hoisting electrical circuit, the combination of a stationary block carrying a set of sheaves, a plurality of traveling blocks each carrying a set of sheaves, cable means reeved about said sheaves to provide mechanical advantage, limit switch means adapted to be electrically connected to said hoisting electrical circuit and operable by upward movement of one of said traveling blocks to limit upward movement of said one traveling block toward said stationary block, first means for combining the plurality of traveling blocks to be moved by the cable means as a unit relative to the stationary block and to said limit switch means, said plurality of traveling blocks

movable as a unit providing one mechanical-advantage ratio, second means for rendering stationary relative to the stationary block the other of said traveling blocks while permitting the said one traveling block to be moved by the cable means relative to the said stationary block, said one traveling block being movable by the cable means independently of said other traveling block, said limit switch means being operable by upward movement of said one traveling block upon the rendering stationary of said other traveling block by said second means and also by upward movement of the one traveling block combined with said other traveling block by said first means, and delaying means for delaying the operation of said limit switch means by the upward movement of said one traveling block uncombined with said other of said traveling blocks until the said other of the traveling blocks reaches a position to be rendered stationary by said second means.

9. In a cable hoist operated by an electric motor having a hoisting electrical circuit, the combination of an upper stationary block rotatably carrying sheaves thereon, a plurality of lower traveling blocks each rotatably carrying sheaves thereon, cable means reeved about the sheaves of said stationary block and said traveling blocks, first means for selectively assembling all of said lower traveling blocks to be moved up and down by the cable means as a unit relative to the upper stationary block, said first means being adapted to permit the traveling blocks alternately to be divided into separate traveling blocks, second means for maintaining at an elevated and fixed position relative to said stationary block a first of said traveling blocks while permitting a second of said traveling blocks to be moved up and down by said cable means relative to the said upper stationary block, limit switch means adapted to be electrically connected to said hoisting electrical circuit and operable by upward movement of said second of said traveling blocks for controlling operation of the hoist to prevent the said second of said traveling blocks from upwardly approaching beyond an arbitrary limited distance of the said upper stationary block, said limit switch means being positioned to be inoperable by said first of said traveling blocks disassembled from said second of said traveling blocks to permit said hoist to be operated while said first of said traveling blocks are maintained at said elevated and fixed position at a distance from said upper stationary block that is less than said arbitrary limited distance, and means for delaying the operation of said limit switch means by upward movement of said second of said traveling blocks until said first of said traveling blocks divided from said second of said traveling blocks may move to said elevated and fixed position for maintenance there by said second means.

10. In a cable hoist operated by an electric motor having a hoisting electrical circuit, the combination of a plurality of first sheaves rotatable on stationary axes, a plurality of second sheaves rotatable on traveling axes, a cable reeved about said first and second sheaves to provide mechanical advantage, first means for selectively including all of said second sheaves while reeved by said cable with said first sheaves to provide one mechanical-advantage ratio and for selectively including some and excluding other of said second sheaves while all are reeved by said cable with said first sheaves, second means for maintaining the excluded second sheaves while reeved by said cable at an elevated fixed position adjacent to said first sheaves while permitting the included second sheaves to move up and down relative to said first sheaves to provide another mechanical-advantage ratio, third means adapted to be connected to said hoisting electrical circuit for automatically discontinuing upward operation of the hoist upon approach of the included second sheaves upwardly within an arbitrary limited distance of the first sheaves while permitting the excluded second sheaves to be maintained at said elevated fixed position adjacent said first sheaves, and fourth means for delay-

ing the discontinuance of upward operation of the hoist by the third means until the excluded second sheaves move to said elevated fixed position for maintenance there by said second means.

11. In a pulley system, the combination of a first pulley block having a plurality of pulleys disposed on axes fixed relative to each other, a second pulley block having a plurality of pulleys, some of the latter pulleys being disposed on axes adapted to be displaced relative to the axes of other of the latter pulleys, the total number of said some of the latter pulleys being equal to the total number of the pulleys in said first pulley block, cable means reeved about the pulleys of said first and second pulley blocks for providing mechanical advantage in moving one pulley block relative to the other, one of said pulley blocks being supported and the other of said pulley blocks being movable relative to the other, first means for maintaining the axes of the said latter pulleys of said second pulley block in fixed relationship to each other, said latter pulleys of the said second pulley block being separable to permit the axes of some of the latter pulleys to be movable relative to the axes of other of the latter pulleys, second means for maintaining the axes of said some of the latter pulleys in fixed relationship to the axes of the pulleys of said first pulley block, said second means including automatic locking means operable upon moving said some of the latter pulleys proximate to said first pulley block and including means for releasing said automatic locking means, the arrangement of pulley blocks and first and second means providing for one mechanical advantage by said cable means and pulley blocks upon the axes of said some of the latter pulleys being maintained in fixed relationship to the other of the latter pulleys of the second pulley block and for another mechanical advantage upon the axes of said some of the latter pulleys being movable relative to the axes of the other of said latter pulleys and maintained in fixed relationship to the axes of the pulleys of said first pulley block.

12. In a hoist, an upper pulley block, a plurality of lower pulley blocks, a cable reeved about said pulley blocks to provide mechanical advantage, load-engageable means carried by one of said lower pulley blocks, means for readily engaging and disengaging said lower pulley blocks, said lower pulley blocks upon being engaged being movable together relative to said upper pulley block to provide a first mechanical advantage ratio, said one lower pulley block being movable relative to the other of said lower pulley blocks upon disengagement of said lower pulley blocks, locking means for locking said other of the lower pulley blocks in fixed relationship to the upper pulley block, means for automatically terminating

hoisting movement of the hoist upon upward movement of said one lower pulley block beyond a point spaced from said upper pulley block, and biasing means for yieldably restraining upward approach of said one lower pulley block beyond said point while said other lower pulley block moves upwardly beyond said point to the position of said fixed relationship, said one lower pulley block, upon disengagement of said lower pulley blocks and the locking of said other of the lower pulley blocks in fixed relationship to the upper pulley block, providing a second mechanical advantage ratio.

13. In a pulley system, the combination of an upper pulley block carrying a plurality of pulleys, said upper pulley block having pulley axes in fixed relationship to each other, a plurality of lower pulley blocks carrying a plurality of pulleys, said lower pulley blocks having a plurality of parallel pulley axes, a load-engaging member carried by one of said lower pulley blocks, a cable reeved on said pulleys to provide mechanical advantage in moving the load-engaging member relative to the upper pulley block, first means for interengaging said lower pulley blocks to position the pulley axes thereof in fixed relationship to each other and for disengaging said lower pulley blocks to permit displacement of the axes of the lower pulley blocks from each other, second means for selectively interengaging the upper pulley block with a lower pulley block other than said one lower pulley block carrying the load-engaging member, means for automatically discontinuing the raising movement of the system upon approach of said one lower pulley block to within a limited distance of the upper pulley block, and biasing means biasing the said one lower pulley block against upward approach to said upper pulley block to within said limited distance during the approach of said other pulley block to a position within said limited distance for interengagement with said upper pulley block, the operation of the said pulley system with the lower pulley blocks interengaged providing one ratio of mechanical advantage and the operation of said pulley system with the lower pulley blocks disengaged and the upper pulley block interengaged with the said lower pulley block other than said one lower pulley block carrying the load-engaging member providing another ratio of mechanical advantage.
